UNITED STATES PATENT OFFICE.

MAX KRISSIEP, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

THREAD-TENSIONING BRAIDING CARRIER.

Application filed June 16, 1925. Serial No. 37,439.

To all whom it may concern:

Be it known that I, MAX KRISSIEP, a citizen of the German Republic, residing at Wyomissing, in the county of Berks and State of Pennsylvania, have invented certain new and useful Improvements in Thread-Tensioning Braiding Carriers, of which the following is a specification.

My invention relates particularly to broiding machine carriers; and it consists mainly in improved thread-tensioning means as hereinafter fully set forth in connection with the accompanying drawing, the novel features of the construction being clearly defined in the subjoined claims.

The main object of the invention is to provide for insuring uniform thread tensioning in such manner as to enable use of the carriers in other than the usual vertical position without impairing their satisfactory operation; and to this end it comprises a spring-tensioned thread-tensioner device which is swingable about the centrally mounted bobbin so as to control the let-off from the latter as indicated in the preferred specific construction illustrated.

Fig. 1 is an elevation of a carrier embodying the invention, a threaded bobbin being shown in position.

Fig. 2 is a longitudinal section, with the bobbin omitted, and showing the thread spreader in section on the line 2—2 of Fig. 1.

Figs. 3 and 4 are cross-sectional views on the lines 3—3 and 4—4 respectively of Fig. 2.

The carrier frame comprises the usual supporting-foot having spaced plates 2, 2 connected by a shuttle piece 3 and provided with a drive-gear-engaging pin 4; the rigid bobbin spindle 6; and threading stem 5 having threading eyes 5^a and 5^b. An ordinary bobbin 7 is indicated as indirectly mounted upon the spindle 6.

In my improved construction the supporting foot is provided with a pawl 10 pivoted thereto at 10^a and normally spring-pressed into stopping engagement with the toothed base portion 11^a of a rotary bobbin holder sleeve 11 upon which the bobbin 7 is tightly fitted. The sleeve portion 11 of this bobbin holder loosely encloses the spindle-mounted sleeve portion 12 of my improved thread-tensioning device; which latter is carried by the supporting foot of the carrier and is connected with the spindle 6 by a tensioning

spring 13 adapted to resist turning movement thereof on the spindle. To provide for varying the tension exerted by this spring 13, the sleeve portion 12 of the thread tensioning device is shown with a relatively rotatable part 12^b attached to the free end of said spindle-connected spring and itself adjustably connected to the base portion 12^a of the sleeve 12 by means of a projection 12^c on the latter engaged in one or another of a series of openings 12^d provided in said part 12^b.

The base 12^a of the spring-tensioned thread tensioner, is formed with an eccentric portion 12^e which engages the pawl 10 during its extreme swinging movement so as to release the bobbin holder 11 for withdrawal of additional thread; and this swinging movement is effected by the pull exerted upon the tensioner through a thread-spreader portion 12^f of the latter, which rises from said base portion 12^a beyond the periphery of the fully loaded bobbin 7, so as to support the thread extending from the bobbin to the threading eyes 5^a 5^b in the threading stem 5. This thread spreading portion 12^f of the swinging tensioner is preferably formed as a cylindrical segment concentric with the mounted sleeve portion 12, so as to provide a considerable contact with the thread passing from the bobbin (Fig. 1) as well as support it free of contact with the bobbin periphery.

The operation of my improved carrier is not affected by its position in the machine; the bobbin, whether standing vertically or horizontally for instance, being intermittently released tooth by tooth as the swinging thread-tensioner is swung by the pull of the spread thread, against its adjusted spring tensioning and with releasing action upon the controlling pawl. The specific construction set forth may obviously be readily modified without departing from the essential features of the invention as set forth in the claims.

What I claim is:

1. In combination with a carrier frame having a fixed bobbin spindle and threading standard, and a movable pawl; a swingable thread tensioner comprising a spring tensioned sleeve on said spindle having a pawl-operating base portion, and a spaced thread-spreading riser from the latter; and a bobbin-holder rotatable upon said sleeve portion

- of the tensioner and having a pawl-engaging base portion.
2. In a carrier as set forth in claim 1, a swingable thread tensioner having an adjustable tensioning-spring connection to the spindle.
3. In a carrier as set forth in claim 1, a swingable thread tensioner having a relatively adjustable sleeve part to which one end of a spindle-connected tensioning spring is attached.
4. In a carrier as set forth in claim 1, a swingable thread tensioner having an eccentrically shaped pawl-operating base portion. 15
5. In a carrier as set forth in claim 1, a swingable thread tensioner having the spaced thread-spreading portion thereof formed as a cylindrical segment concentric with its sleeve portion. 20

In testimony whereof I affix my signature.
MAX KRISSIEP.
